UNITED STATES PATENT OFFICE

1,969,563

APPARATUS FOR LUBRICATING
WIRE ROPE

Halsey G. Kinder, Kenosha, Wis., assignor to
Macwhyte Company, Kenosha, Wis., a corpora-
tion of Illinois

Application October 16, 1931, Serial No. 569,221

2 Claims. (Cl. 117—16)

This invention relates to a method of and an apparatus for lubricating strands of wire rope.

It has for one object to provide means for and a method of lubricating the several strands as they are about to be formed into a rope. Another object is to provide means for applying to the strands a cold lubricant. In this sense the word "cold" means that the lubricant has not been heated. It is not artificially cooled but is applied at room temperature. In the past, in the manufacture of wire rope, it has been customary to heat the lubricant so as to render it more fluid and so that it can be poured or "flowed". For many reasons this has proven unsatisfactory and it is one of the objects of the present invention, therefore, to avoid the necessity of heating the grease or other lubricant and to provide an apparatus and a method for applying it cold.

Another object is to provide means for positively supplying cold grease to the entire surface of each strand of the wire. A further object is to do this just prior to the moment when the strands are formed or wound into the rope.

Other objects will appear from time to time in the specification and claims.

My invention is illustrated more or less diagrammatically in the accompanying drawings, wherein:—

Figure 1 is a side elevation of one end of a rope making machine, with parts omitted, parts broken away and parts in section, showing the lubricant supplying device in position;

Figure 2 is an end elevation showing the same machine.

Fig. 3 is an enlarged section along line 3—3 of Fig. 2.

Like parts are designated by like characters throughout the specification and drawings.

A indicates a foundation upon which the machine is supported. Any foundation may be provided so long as it is sufficient in size and strength to carry the load. A¹ is a standard supported upon the foundation and serving to carry and position a portion at least of the rope making machine. The details of this machine are not shown as they form no particular part of the present invention. It is sufficient for the purposes of the present invention that means are

provided for supplying the rope strands and for forming them into the rope. A² is a forming member which is mounted for rotation and through which a number of strands B pass. The strands are joined at a point B¹ where they enter

a die or other forming member B². This die may

be of any suitable form and its details form no part of the present invention. It is carried in a frame member B³ and is preferably removably held in position therein by a locking and adjusting screw B⁴ upon which a thumb nut B⁵ may be mounted. B⁶ B⁷ are rods preferably mounted in the standard A¹ and projecting outwardly from it and serving to carry the frame member B³ which is provided with portions B⁷ to fit upon or embrace the rods B⁶. B⁸ are set screws formed in the members B⁷ by means of which the frame may be removably fixed in position upon the rods B⁶.

A support C may be mounted upon the foundation A and serves to carry the lubricant supply- 70 assembly and its driving means. It may be driven in any suitable manner. It may, for ex- ample, be driven from the mechanism which drives the rope making machine or it may be separately driven. As shown herewith a motor 75 C¹ and a shaft C² are provided for driving the lubricant supplying machine. A pinion C³ is mounted on the shaft C². A gear housing box is provided beneath the lubricant assembly and it is preferably formed to serve as the bottom of 80 the lubricant hopper or container. It may be formed with a generally annular portion D across which extends a web member D¹ and within which one or more open spaces D² may be provided.

The member D¹ is perforated as at D³ and pro- 85 vided at its upper end with a socket portion D⁴ which may also serve as a support and receiving means for a bearing or bearing race. Extending downwardly from the annular portion D, prefer- ably formed integrally with it and forming in 90

effect a generally cylindrical housing, is a portion D⁵. A pair of bearing portions D⁶ D⁷ is formed in it. The member D⁶ is preferably closed at its outer end and the member D⁷ is open and interiorly threaded as at D⁸ to receive a packing 95 gland D⁹. At its bottom the cylindrical portion D⁵ is closed by a preferably removable bottom plate D¹⁰.

A shaft E is positioned in the bearings D⁶ D⁷. It carries at its outer end a gear E¹ which meshes 100 with the pinion C³ on the motor shaft C². Ad- jacent its opposite end and within the housing D⁵ the shaft E carries a beveled pinion E².

F is a lubricant conveyor shaft positioned with- in the perforation D³ in the cross member D¹ and 105 preferably having fixed upon it a laterally ex- tends flange F¹. A bearing F² which may be of any suitable type but is here shown as an anti-friction bearing, is positioned within the socket D⁴ of the cross member D¹ and beneath 110

the flange F^1 and thus serves to support the shaft F . At its lower end the shaft F carries a beveled gear F^3 which meshes with the beveled pinion E^2 on the shaft E . A helical portion F^4 is mounted upon the shaft F and may extend throughout the major portion of its length.

G is an annular supporting member provided with one or more upwardly extending arms G^1 which preferably are inclined inwardly and converge toward a hollow collar member G^2 having within it an inwardly extending flange or ledge G^3 .

H is a tube positioned within the collar member G^2 and preferably resting upon the flange or ledge G^3 . It may be fixed in position therein in any suitable fashion.

I is a varying cylindrical portion of an irregularly shaped tubular member which has an interior diameter of approximately the same as the exterior diameter of the tube H . It is positioned over this tube and may be arranged for telescopic adjustment along it. I^1 is an upper portion of the member I preferably formed integrally with it and flattened so that in one plane it is wider than the portion I and in a plane preferably at right angles thereto it is narrower than the member I . The flattened portion I^1 is notched or cut away at its upper end as at I^2 . This cut away portion is preferably generally rounded and may have a circular bottom and may or may not have straight sides. The members I^3 are preferably formed on the flattened portion I^1 and supported upon the frame member B^3 , although the flattened tube may be supported in any other suitable manner. It is preferably positioned as shown in Figure 1 in particular, so that the wire strands B , as they pass to the forming die and as they move to be formed into the rope, pass through the notched or cut away portion I^2 .

J is a lubricant container. It may be of any suitable shape but is shown as formed with sloping sides. It has an open top and may have an opening J^1 in its bottom and may also have an inwardly extending flange member J^2 about the opening J^1 . It rests upon and is preferably secured to the annular member D .

It will be realized that whereas I have herewith shown and described a practical operative device, nevertheless many changes might be made in the size, shape, number and disposition of parts without departing from the spirit of my invention and I wish, therefore, that my showing be taken as in a sense diagrammatic.

55 The use and operation of my invention are as follows:

60

65

70

75

The lubricant supplying apparatus is assembled as shown at a suitable point with relation to a rope making machine, so that the several strands of the rope, before they are formed into the rope, pass above and adjacent to the tubular assembly. The lubricant container is filled with lubricant and the shaft carrying the helices is rotated. The shaft picks up a quantity of lubricant and carries it upwardly through the tubular assembly, discharging it out of the open top. Since the strands of the rope are passing above and adjacent the open top, the lubricant is discharged against them and they thus pass through a body of lubricant and are fully lubricated on all sides and move thence to the point where they are made into the rope. Each strand is thus completely lubricated on all sides and the rope formed of them is thus formed of lubricated strands and is itself lubricated thereby internally and externally. That portion of the lubricant which does not adhere to the strands, falls back into the lubricant container or vat and may move again through the tubular assembly toward its point of discharge against the strands.

Since the driving means for the lubricant supply apparatus is positioned in effect within the lubricant housing or vat, it is itself lubricated by that lubricant. It might, of course, be made in a separate chamber.

I claim:

1. In combination with a rope forming machine, provided with means for forming a rope from a plurality of strands, means for lubricating said strands with relatively solid lubricant, individually, prior to their formation into the rope, said lubricating means including a lubricant container and means for forcing lubricant from the container to the individual strands, said forcing means including a tubular enclosing means, formed of a plurality of relatively telescopic parts, and mounted to discharge lubricant against said strands and shaped to embrace them, and a conveyor positioned within said tubular enclosing means and adapted to convey lubricant therethrough and means for driving said conveyor.

2. A lubricating unit for lubricating the wires of stranding and cabling machines, comprising a lubricant container and a conveyor movably mounted within said container, adapted forcibly to convey and apply lubricant to said strands, and means adjacent said container, and about said strands, for guiding and constraining the lubricant until it has been applied to the strands.

HALSEY G. KINDER.
